BY *D. Murphy*
Watson E. Coleman
ATTORNEY.

UNITED STATES PATENT OFFICE.

BERTRAND P. MURPHY, OF DONNYBROOK, NORTH DAKOTA.

DUMPING MECHANISM.

Application filed April 21, 1923. Serial No. 633,687.

To all whom it may concern:

Be it known that I, BERTRAND P. MURPHY, a citizen of the United States, residing at Donnybrook, in the county of Ward 5 and State of North Dakota, have invented certain new and useful Improvements in Dumping Mechanisms, of which the following is a specification, reference being had to the accompanying drawings.

10 This invention relates to certain improvements in dumping mechanisms and has relation more particularly to a mechanism of this general character especially designed and adapted for use in connection with the 15 scale platform of a grain elevator and it is an object of the invention to provide a novel and improved mechanism of this general character which may be readily operated either manually or by power.

20 Another object of the invention is to provide novel and improved means of this general character wherein easy dumping of a vehicle is accomplished by elevation of the 25 track timbers or logs from the front of the platform.

An additional object of the invention is to provide a novel and improved device of this general character wherein the driving means will effect a power operation of 30 the mechanism free of the scale platform during a weighing operation.

The invention consists in the details of construction and in the combination and arrangement of the several parts of my 35 improved dumping mechanism whereby certain important advantages are attained and the device rendered simpler, less expensive, and otherwise more convenient and advantageous for use, as will be hereinafter 40 more fully set forth.

The novel features of my invention will hereinafter be definitely claimed.

In order that my invention may be the better understood, I will now proceed to describe the same with reference to the accompanying drawings, wherein:

Figure 1 is a view partly in side elevation and partly in section illustrating a dumping mechanism constructed in accordance with an embodiment of my invention;

Figure 2 is a view similar to Figure 1 showing certain of the parts in a second position;

Figure 3 is a fragmentary view partly in section and partly in elevation illustrating

the brake mechanism associated with the manual operating means;

Figure 4 is a view in bottom plan of the structure as illustrated in Figure 1, 60

Figure 5 is a view partly in section and partly in rear elevation of the device as herein disclosed.

As disclosed in the accompanying drawings, P denotes a scale platform in its entirety of a general type employed in connection with grain elevators and as the mounting and general operation of the scale platform P forms no part of my present invention it is believed that a detailed 70 description and illustration thereof is unnecessary.

The platform P is positioned over a pit A and between the flooring 1. The platform comprises the beams 2, said beams 75 being arranged in pairs at opposite sides of the platform and positioned between the beams 2 of each pair is the track timber or log 3. The log 3 is pivotally connected with the adjacent beams 2 at a point in 80 relatively close proximity to the rear end of the platform P by a pin 4 or its equivalent, whereby said timber or log 3 is capable of swinging movement in a vertical direction.

Secured to and depending from the opposite end portion of each of the timbers or logs 3 is an arcuate rack 5 reinforced by the bracket 6. Meshing with each of the racks 5 is a pinion 7 mounted upon a shaft 8, said 90 shaft being disposed below and transversely of the platform P and supported by the arms or brackets 9 depending from the outer beams 2. The shaft 8 as herein disclosed is provided entirely therealong with the key 95 way or groove 11 in which is adapted to be engaged a key 12 for each of the pinions 7 whereby said pinion is locked to the shaft 8. This mounting of the pinions permits a 100 desired adjustment in order to properly apply my improved mechanism to platforms of varying sizes.

The shaft 8 is held against endwise movement through the medium of the collars 14 mounted thereon and contacting with the 105 arms or brackets 9, said collars being held in fixed position upon the shaft 8 by the set screws 15 or the like.

Positioned below and extending longitudinally of a side beam 2 and supported by the 110 arms or brackets 16 depending from said beam is a second shaft 17 provided at its

forward end portion with a clutch member 18 herein disclosed as of a friction type. The shaft 17 is held against endwise movement by the collars 19 contacting with the 5 arms or brackets 16, said collars being locked to the shaft 17 by the set screws 20. The opposite or rear end portion of the shaft 17 has fixed thereto a worm 21 meshing with a worm gear 22 fixed to the adjacent end portion 10 of the shaft 8 so that upon requisite rotation of the shaft 17, the shaft 8 will be rotated in a direction to raise or elevate the timbers or logs 3 to effect a dumping of a vehicle positioned thereon.

15 A vertically disposed standard 23 is secured by the bracket 24 or the like to the side beam 2 of the platform P adjacent to the shaft 17, said standard extending above and below the platform and having the shaft 20 17 disposed through the lower portion thereof. Keyed or otherwise secured to the shaft 17 adjacent to the standard 23 is a sprocket wheel 25 around which passes a chain 26 which is also disposed over a sprocket wheel 25 27 arranged adjacent to the upper end portion of the standard 23. This sprocket 27 is fixed to a shaft 28 carried by a bracket 29 secured to the upper end portion of the standard 23 and also fixed to the shaft 28 is a 30 hand wheel 30 whereby the shaft 17, when desired, may be manually driven.

Substantially in alignment with the shaft 17 is a shaft 31 supported by the arms or brackets 32 depending from a beam 33 of a 35 flooring 1, said shaft being held against endwise movement by the collars 34 arranged for contact with the arm or brackets 32 and fixed to said shaft 31 by the set screws 35 or the like. As herein disclosed the shaft 31 40 has keyed or otherwise fixed thereto a pulley 36 adapted to be coupled with a suitable source of power. The end portion of the shaft 31 adjacent to the shaft 17 has keyed thereon for rotation with said shaft but 45 movable lengthwise thereof a clutch member 37. This clutch member 37 is of a friction type and coacts with the clutch member 18 hereinbefore referred to whereby the shaft 17 if preferred may be power driven. 50 The requisite movement of the clutch member 37 into and out of engagement with the clutch member 18 is herein disclosed as accomplished through the medium of a lever

38 operatively engaged with said clutch member 37 and pivotally supported by the 55 beam 33 of the flooring 1. The lever 38 also extends a desired distance above the flooring 1 so that it may be readily and conveniently manipulated. When the clutch member 37 is free from the clutch member 18 the shaft 31 and the parts carried thereby are entirely 60 separated from the platform P and particularly during a weighing operation.

Fixed to the shaft 28 and preferably between the arms of the bracket 29 is a band 65 wheel 39 with which is associated the brake band 40, one end portion of the band being connected as at 41 to the bracket 29 and having its opposite end portion secured to a 70 brake handle 42 pivotally attached to the bracket 29. By proper manipulation of the handle 42 the rotation of the shaft 17 may be effectively controlled and especially during the lowering movement of the track timbers or logs 3.

75 The standard 23 is further braced by the rods 43 interposed between the standard 23 at a point above the adjacent beam 2.

From the foregoing description it is though to be obvious that a dumping mechanism constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement 80 and formation of the several parts herein shown in carrying out my invention in practice except as hereinafter claimed.

I claim:—

The combination with a scale platform, 85 track timbers pivotally supported thereby, means carried by the platform for moving said track timbers about their pivots, manually operated means carried by said platform for operating said first named means, 100 and power driven means supported independently of the platform for operating said first named means.

In testimony whereof I hereunto affix my signature.

BERTRAND P. MURPHY.
